ATTORNEYS

UNITED STATES PATENT OFFICE.

WILLIAM O. McELROY, JR., AND JOSEPH F. TROPEA, OF RIVEREDGE, NEW JERSEY.

TOY VEHICLE.

Application filed August 27, 1923. Serial No. 659,645.

To all whom it may concern:

Be it known that we, WILLIAM O. McELROY, Jr., and JOSEPH F. TROPEA, both citizens of United States, residing at Riveredge, 5 in the county of Bergen and State of New Jersey, have invented new and useful Improvements in Toy Vehicles, of which the following is a specification.

This invention relates to improvements in 10 toy vehicles and has for an object the provision of a vehicle which is constructed in imitation of a boat and which is provided with propelling means, so that a child may occupy and propel the boat and control its 15 direction of travel.

Another object of the invention is the provision of means whereby, when the boat is propelled, a rocking motion will be imparted thereto to simulate the movement of 20 a boat upon the waves.

Another object of the invention is the provision of novel means for steering the vehicle or boat, so that its direction of travel may be readily controlled.

25 Another object of the invention is the provision of a novel form of propelling means which is operated in imitation of the action of rowing.

With the above and other objects in view, 30 the invention further includes the following novel features and details of construction, to be hereinafter more fully described, illustrated in the accompanying drawings and pointed out in the appended claims.

35 In the drawings:—

Figure 1 is a side elevation of the invention shown in the form of a row boat.

Figure 2 is a top plan view of the same.

40 Figure 3 is a vertical longitudinal sectional view.

Figure 4 is a transverse section taken substantially on the line 4—4 of Figure 2.

Figure 5 is a section taken substantially on the line 5—5 of Figure 2.

45 Figure 6 is an enlarged fragmentary horizontal section taken substantially on the line 6—6 of Figure 3.

Figure 7 is a detail section taken substantially on the line 7—7 of Figure 6.

50 Figure 8 is a transverse section taken substantially on the line 8—8 of Figure 6.

Figure 9 is a detail section on the line 9—9 of Figure 4.

Figure 10 is an enlarged detail section

taken substantially on the line 10—10 of 55 Figure 5.

Figure 11 is an enlarged detail elevation showing a portion of the propelling means.

Figure 12 is an enlarged fragmentary section showing another portion of the propelling means.

Figure 13 is a central longitudinal section showing a modified form of the invention.

Figure 14 is a plan view of the same.

Figure 15 is a section taken substantially 65 on the line 15—15 of Figure 14.

Figure 16 is an enlarged sectional view on the line 16—16 of Figure 5.

Referring to the drawings in detail and especially to Figures 1 to 12 inclusive, it will be seen that the body of the toy as disclosed in these figures is shaped to conform to the shape of a boat of the type commonly referred to as a row boat, the said body being indicated at 20. The body is mounted 75 upon wheels 21 and the latter support a front axle 22 and a rear axle 23, both of said axles extending through vertically arranged slots 24 which are provided with oppositely arranged rollers 25, the latter engaging the axles for a purpose to be herein-after understood.

The front axle 22 is swung from a bar or shaft 26 which extends transversely across and is secured to the opposite sides of the 85 body 20. This shaft has loosely mounted thereon the upper ends of hanger rods 27, the said upper ends being provided with eyes 28 which loosely receive the bar or shaft 26 and which is held against movement longitudinally upon the shaft or bar by means of spaced collars 29. The lower ends of the rods 27 are connected to the bands 30 of eccentrics 31, the latter being keyed upon the axle 22, while anti-friction elements 32 95 are interposed between the band and eccentric. As will be seen by reference to Figure 4 of the drawings, the eccentrics are oppositely arranged so that they will operate in opposition to one another.

100 Mounted upon the front axle 22 are gears 33. These gears are formed to rotate upon the axle and are held against movement longitudinally thereof by means of collars 34. Secured to the axle 22 are ratchet 105 wheels 35, while the gears 33 carry spring pressed dogs 36. These dogs engage the ratchet wheels 35 so that when the gears 33

are rotated in one direction they will be locked to the axle 22 but will be free when rotated in an opposite direction. The dogs 36 and the ratchet wheels 35 are reversely disposed, so that one gear 33 will be locked to the shaft when the gear is rotated in one direction and the other gear will be locked when rotated in an opposite direction.

For the purpose of rotating the gears 10 there is provided relatively offset upper and lower rack bars 37, one of which engages each of the gears 33. These rack bars are connected by side plates 38 and the latter are provided with elongated slots 39 for 15 the accommodation of the axle 22, so that the rack bars 37 and side plates 38 provide a housing which encloses the gears and ratchet mechanism. Secured to this housing is one end of a rod 39, the opposite end 20 of which is secured to one end of a lever 40, the securing means being in the form of a ball and socket joint 41. The lever 40 is mounted upon a shaft 42 which extends transversely across the boat and has its opposite ends mounted in bearings 43. Secured to the upper end of the lever 40 is a cross bar 44, while pivotally secured as at 45 to the opposite ends of this cross bar are oars or levers 46 having handles 47. 25 The oars 46 are mounted within oar locks 48 secured to the opposite side edges of the boat, pins 49 carried by the oar locks extending through elongated slots 50 in the oars so that the latter are pivotally and 30 slidably mounted.

The rear axle 23 extends upon opposite sides of the boat through the slots 24 and has pivotally secured to its outer end spindles 51. Extending from these spindles 40 are arms 52 and the latter are connected to an arm 53 through the medium of connecting rods 54 whose opposite ends are pivotally connected to the arms 52 and 53 respectively. The arm 53 extends from a relatively short rock shaft 54' which is mounted in a bearing sleeve 55 and the latter is secured to the axle 23 by means of bracket arms 56. The upper end of the rock shaft 54' has mounted thereon a steering rod 57 50 which serves as a means whereby the shaft 54' may be rocked to impart pivotal movement to the spindles 51 to control the direction of travel of the vehicle.

The axle 23 is pivotally mounted as shown 55 at 58 upon a bracket 59 which extends upwardly from the bottom of the boat.

The boat may be provided with seats 60, one of which may be placed in the bow, one in the stern and one amidships.

60 The occupant of the last mentioned seat will be in convenient position to grasp the handles 47 of the oars 46 and may move the latter in imitation of rowing. This will, through the lever 40 impart a reciprocatory 65 movement to the rod 39 so that the gear

frame and its racks 37 will be moved longitudinally for rotation of the gears 33. When moved in one direction, one of the gears 33 will be locked to the axle 22 so as to rotate said axle and when moved in an opposite direction the other gear will be rotated so that a continuous driving movement will be imparted to the axle. At the same time, the eccentrics 31 will be operated and the boat will be rocked on its longitudinal center through the operation of these eccentrics. The child's feet may be placed upon the steering bar 57 so that the boat may be steered as desired. The sides of the boat are provided with openings 61 for the passage of the rods 54.

In Figures 13, 14 and 15, the body 62 is shown in the form of a boat having its forward portion decked over as at 63 in imitation of a launch. The body is supported upon a front axle 64 and a rear axle 65, the latter being provided with cranks 66 which have secured thereto connecting rods 67. These rods are connected to crank arms 68 which are provided with pedals 69, so that an occupant of a seat 70 which is arranged within the boat may operate the crank arms to rotate the shaft 65. The shaft 65 is hung from a shaft or bar 71 through the medium of hanger rods 72 and eccentrics 73 after the manner of the first described form of the invention, so that as the axle 65 is rotated a rocking motion will be imparted to the body 62. The axles 64 and 65 extend through slots 74 in the side 90 of the boat.

The front axle 64 has pivotally secured to each end thereof spindles 75 from which extend arms 76 and these arms are connected by means of rods 77 with an arm 78, 105 the last mentioned arm extending from the lower end of a steering post 79 which is mounted in a steering column 80. The column 80 is secured to the axle 64 by means of brackets 81, while the steering post has 110 secured upon its upper end a wheel 82. The axle 64 is pivotally mounted as shown at 83 in a bracket 84 which extends from the bottom of the boat.

In this form of the invention, the operator faces the bow of the boat and utilizes his feet to provide power for propulsion and steers the vehicle by hand, the manner of control being substantially opposite that in the first described form of the invention. 120

The invention is susceptible of various changes in its form, proportions and minor details of construction and the right is herein reserved to make such changes as properly fall within the scope of the appended claims.

Having described the invention what is claimed is:—

1. A toy vehicle comprising a body, wheel supported axles including a driving axle 130

- for supporting the body, means whereby the driving axle may be operated, means whereby the direction of travel of the vehicle may be controlled, and eccentric means 5 mounted upon the driving axle whereby operation of the latter will impart a lateral rocking movement to the body.
2. A toy vehicle comprising front and rear wheel supported axles including a driving axle, a body supported by the axles and capable of relative movement, means whereby the driving axle may be operated, means whereby the direction of travel of the vehicle may be controlled, and means including 10 oppositely movable eccentrics mounted upon the driving axle whereby operation of the latter will impart a rocking movement to the body.
3. A toy vehicle comprising front and rear wheel supported axles including a driving axle, a body supported by the axles and capable of relative movement, means whereby the driving axles may be operated, means whereby the direction of travel of the vehicle may be controlled, eccentrics mounted 15 upon the driving shaft, a stationary shaft extending transversely of the body, and means connecting the eccentrics and stationary shaft, whereby operation of the driving axle will impart a rocking movement to the body.
4. A toy vehicle comprising front and rear wheel supported axles including a driving axle, a body supported by the axles and capable of relative movement, means whereby the driving axle may be operated, means whereby the direction of travel of the vehicle may be controlled, a bar mounted 20 above the driving axle, eccentrics mounted upon said driving axle and hanger rods connecting the eccentrics and bar, whereby operation of the driving axle will impart rocking movement to the body.
5. A toy vehicle comprising front and rear wheel supported axles including a driving axle, a body supported by the axles and capable of relative movement, means including 25 pivotally mounted oppositely extending levers operatively connected to the axle rotating means for operating the latter, means whereby the direction of travel of the vehicle may be controlled and means whereby operation of the driving axle will impart relative movement to the body.
6. A toy vehicle comprising front and rear wheel supported axles including a driving axle, a body supported by the axles and capable of relative movement, means including double acting ratchet controlled gears whereby the driving axle may be rotated, means whereby the direction of travel of the vehicle may be controlled, and means whereby operation of the driving axle will impart relative movement to the body.
7. A toy vehicle comprising front and rear wheel supported axles including a driving axle, a body supported by the axles and capable of relative movement, gears loosely mounted upon the driving axle, racks engaging said gears, means whereby the racks may be reciprocated to rotate the gears, means for alternately locking the gears to the axle to provide continuous rotation when the racks are reciprocated, means whereby the direction of travel of the vehicle may be controlled, and means whereby rotation of the driving axle will impart relative movement to the body.
8. A toy vehicle comprising front and rear wheel supported axles including a driving axle, a body supported by the axles and capable of relative movement, gears loosely mounted upon the driving axle, racks engaging said gears, a pivotally mounted lever, a rod connecting one end of the lever and racks, a bar secured to the opposite end of the lever, levers pivotally secured to each end of the bar, means for pivotally mounting the last mentioned levers, whereby operation of the latter will reciprocate the racks to rotate the gears, means for alternately locking the gears to the axle to provide continuous rotation when the racks are reciprocated, means whereby the direction of travel of the vehicle may be controlled, and means whereby rotation of the driving axle will impart relative movement to the body.

In testimony whereof we have affixed our signatures.

WILLIAM O. McELROY, JR.
JOSEPH F. TROPEA,
